CONVERSION OF HYDROCARBON OILS

Kenneth Swartwood, Chicago, Ill., assignor to
 Universal Oil Products Company, Chicago, Ill.,
 a corporation of Delaware

Application October 26, 1933, Serial No. 695,268
 Renewed March 18, 1935

7 Claims. (Cl. 196—49)

This invention relates to an improved process and apparatus for the fractional distillation of hydrocarbon oils of relatively wide boiling range, such as crude petroleum, accompanied by pyrolytic conversion of all but the desirable low-boiling fractions of the charging stock and further conversion of the insufficiently converted intermediate products of the process to produce high yields of desirable low-boiling distillate, such as motor fuel of high antiknock value, and good quality fuel oil residue.

One specific embodiment of the present invention comprises subjecting hydrocarbon oil, such as crude petroleum, to fractional distillation, recovering its desirable low-boiling fractions, subjecting its intermediate fractions to conversion temperature at superatmospheric pressure in a heating coil, introducing the resulting products into a reduced pressure vaporizing chamber, subjecting bottoms from the topping operation to conversion temperature at superatmospheric pressure in a separate heating coil, subjecting the resulting products to vaporization and fractionation, subjecting fractionated vapors of the desired end-boiling point to condensation and collecting the resulting products, returning low-boiling components of the reflux condensate produced by said fractionation to the first mentioned heating coil for further conversion, supplying bottoms from said fractionation and vaporizing stage to said reduced pressure vaporizing chamber, subjecting vaporous products from the vaporizing chamber to fractionation, subjecting fractionated vapors of the desired end-boiling point to condensation and collecting the resulting products, subjecting reflux condensate resulting from the last mentioned fractionating stage to conversion temperature at superatmospheric pressure in another separate heating coil and, if desired, a communicating reaction chamber and introducing the resulting vaporous and liquid conversion products into said reduced pressure vaporizing chamber.

One of the features of the invention is the provision for subjecting the bottoms from the topping operation (high-boiling fractions of the charging stock) to a mild cracking or viscosity breaking operation in a single pass through a heating coil and subjecting the resulting residual conversion products to further vaporization for the production of good quality fuel oil.

Another advantageous feature of the invention resides in the provision for subjecting intermediate fractions of the charging stock, resulting from the topping operation, to conversion, to-

gether with corresponding intermediate fractions resulting from the relatively mild once-through conversion of the high-boiling fractions of the charging stock, to conversion under independently controlled conditions in a single pass through a separate heating coil.

Another feature of the invention provides for cooling the hot conversion products from the heating coil to which the intermediate fractions of the charging stock and intermediate conversion products from the first or relatively mild cracking stage of the process are supplied to a temperature at which their excessive conversion is prevented, by commingling therewith high-boiling conversion products resulting from the first cracking stage of the process whereby to heat the latter sufficiently to effect their mild continued conversion and substantial further vaporization.

The accompanying diagrammatic drawing illustrates one specific form of apparatus in which the process may be practiced.

Referring in detail to the drawing, raw oil charging stock for the process, preferably comprising an oil of relatively wide boiling range, such as crude petroleum, for example, is heated to a temperature sufficient to effect its substantial vaporization by a well known means, not illustrated in the drawing, and is supplied in heated state through line 1 and valve 2 to topping and fractionating column 3, wherein it may be separated into low-boiling, high-boiling and intermediate fractions.

Any desired low-boiling fractions of the charging stock, comprising, for example, gasoline or light gasoline fractions of satisfactory antiknock value, may be withdrawn from the upper portion of column 3 through line 4 and valve 5 to condenser 6, wherein they are subjected to condensation and cooling. The resulting distillate and gas passes through line 7 and valve 8 to collection and separation in receiver 9. Uncondensable gas may be released from the receiver through line 10 and valve 11. Distillate may be withdrawn from this zone through line 12 and valve 13 to storage or to any desired further treatment. If desired, a regulated portion of the distillate collected in receiver 9 may be recirculated by well known means, not shown in the drawing, to the upper portion of column 3 to assist cooling and fractionation of the vapors in this zone and to maintain the desired vapor outlet temperature from the column, thus regulating the end-boiling point of the overhead distillate product.

- Intermediate fractions of the charging stock, comprising, for example, any gasoline or high-boiling gasoline fractions of inferior antiknock value contained in the charging stock as well as, 5 if desired, higher boiling components of the charging stock such as kerosene or kerosene distillate, light gas oil and the like, are withdrawn from one or a plurality of suitable intermediate points in column 3, for example, through line 14 10 and valve 15 to pump 16 by means of which this material is supplied through line 17 and valve 18 to conversion in heating coil 19.
- A furnace 20 of any suitable form supplies the required heat to the oil passing through heating 15 coil 19 to bring it to the desired conversion temperature, preferably at a substantially superatmospheric pressure and the heated products are discharged through line 21 and valve 22 into vaporizing chamber 23. Preferably the stream of 20 hot conversion products passing through line 21 is cooled sufficiently to prevent its excessive further conversion, by the introduction of a stream of cooler oil to this line, as will be hereinafter more fully described, and preferably a substantially 25 reduced pressure relative to that employed at the outlet from heating coil 19 is utilized in chamber 23 in order to retard conversion and assist vaporization of the products supplied to this zone.
- High-boiling fractions of the charging stock, 30 including its components boiling above the range of the intermediate fractions which it is desired to subject to conversion in heating coil 9, as already described, are withdrawn from the lower portion of column 3 through line 24 and valve 25 to pump 26, by means of which they are supplied through line 27 and valve 28 to conversion in heating coil 29, preferably under milder conversion conditions than those employed in heating coil 19.
- The high-boiling fractions of the charging stock passing through heating coil 29 are brought to the desired conversion temperature by means of heat supplied from a furnace 30 of any suitable 45 form and the heated products are discharged through line 31 and valve 32 into vaporizing and fractionating column 33 wherein liquid conversion products are separated from the vapors and the latter are subjected to fractionation.
- Fractionated vapors of the desired end-boiling point, preferably comprising conversion products within the boiling range of motor fuel and of good antiknock value, are withdrawn from the upper portion of column 33 through line 34 and valve 35 and are subjected to condensation and cooling in condenser 36. The resulting distillate and gas passes through line 37 and valve 38 to collection and separation in receiver 39. Uncondensable gas may be released from the receiver 60 through line 40 and valve 41. Distillate may be withdrawn from receiver 39 through line 42 and valve 43 to storage or to any desired further treatment. When desired, a regulated portion of the distillate collected in receiver 39 may be recirculated by well known means, not shown in the drawing, to the upper portion of column 33, to assist cooling and fractionation of the vapors and to maintain the desired vapor outlet temperature from the column, thus regulating the end-boiling 70 point of the overhead product.

Intermediate fractions of the vaporous conversion products supplied to column 33 and condensed in this zone as low-boiling reflux condensate, comprising, for example, any motor fuel 75 or high-boiling motor fuel fractions of inferior

antiknock value as well as, when desired, higher boiling fractions such as pressure distillate bottoms, light gas oil and the like, are withdrawn from any suitable intermediate point or points in column 33, for example, through line 44 and valve 45 to pump 46 by means of which they are returned through line 47, valve 48 and line 17 to further conversion in heating coil 19, together with intermediate fractions of the charging stock, supplied to this zone as previously described. 10

High-boiling components of the conversion products supplied to column 33, including non-vaporous residual liquid products as well as high-boiling fractions of the reflux condensate removed from the vapors undergoing fractionation 15 in column 33, are withdrawn from the lower portion of this zone through line 49 and valve 50 to pump 51 by means of which they are introduced through line 52 and valve 53 into line 21, to commingle with the stream of highly heated 20 conversion products from heating coil 19, serving to cool the latter, as previously mentioned, to a temperature sufficient to prevent its excessive further conversion and at the same time providing a means of heating the heavy oils from 25 column 33 to a relatively mild conversion temperature or at least to a temperature sufficient to affect their substantial further vaporization in vaporizing chamber 23, to which the commingled oils from line 21 are supplied as previously described. 30

Conversion products from another source are also supplied to chamber 23, as will be later more fully described, and separation of the vaporous products and a non-vaporous residue is accomplished in this zone. The residual liquid may be withdrawn from the lower portion of chamber 23 through line 54 and valve 55 to cooling and storage or to any desired further treatment. Vaporous products pass from the upper portion of 40 chamber 23 through line 56 and valve 57 to be subjected to fractionation in fractionator 58.

Components of the vaporous products supplied to fractionator 58 of the desired characteristics, 45 preferably comprising materials within the boiling range of motor fuel and of good antiknock characteristics, are withdrawn as fractionated vapors from the upper portion of this zone through line 59 and valve 60 to condenser 61, wherein they are subjected to condensation and 50 cooling. The resulting distillate and gas passes through line 62 and valve 63 to collection and separation in receiver 64. Uncondensable gas may be released from receiver 64 through line 65 and valve 66. Distillate may be withdrawn 55 from the receiver to storage or to any desired further treatment through line 67 and valve 68. If desired, a regulated portion of the distillate collected in receiver 64 may be recirculated by well known means, not shown in the drawing, to 60 the upper portion of fractionator 58 to serve as a cooling and refluxing medium to assist fractionation of the vapors in this zone and to maintain the desired vapor outlet temperature, thus regulating the end-boiling point of the final light 65 distillate product from this zone.

Components of the vaporous products supplied to fractionator 58, boiling above the range of the desired overhead product collected in receiver 64, are condensed in this zone as reflux condensate 70 which is withdrawn from the lower portion of the fractionator through line 69 and valve 70 to pump 71. Pump 71 supplies the reflux condensate from fractionator 58 through line 72 and valve 73 to heating coil 74, wherein it is subjected 75

to further conversion, preferably at superatmospheric pressure, by means of heat supplied from a furnace 75 of any suitable form. The hot conversion products are discharged from heating coil 74 through line 76 and may pass, all or in part, either through line 77 and valve 78 into reaction chamber 79 or through line 80, valve 81 and line 21 direct to vaporizing chamber 23.

Reaction chamber 79, when utilized, is preferably operated at a superatmospheric pressure, which may be substantially equalized with that maintained at the outlet from heating coil 74 or may be somewhat reduced. Although not illustrated, chamber 79 is also preferably well insulated to prevent the excessive loss of heat from this zone by radiation so that conversion of the products supplied thereto from heating coil 74, and more particularly their vaporous components, may continue in the reaction chamber. In the case here illustrated, both vaporous and liquid conversion products are withdrawn in commingled state from the lower portion of chamber 79 through line 82 and valve 83, from which they pass through line 80 and line 21 into vaporizing chamber 23, together with the commingled products from heating coil 19 and from the lower portion of column 33.

Any desired pressure ranging from substantially atmospheric or subatmospheric to a superatmospheric pressure of 200 pounds, or more, per square inch, may be employed for the fractional distillation of the charging stock in the topping and fractionating equipment. Preferably a conversion temperature of from 900 to 1050° F., or thereabouts, is employed at the outlet from the heating coil to which intermediate fractions of the charging stock and low-boiling fractions of the reflux condensate from the first or low temperature conversion stage of the process are supplied, with a superatmospheric pressure, measured at this point in the system, preferably within the range of 300 to 1000 pounds, or thereabouts, per square inch, although, when desired, lower pressures down to substantially atmospheric may be employed in this zone. A conversion temperature within the range of 800 to 950° F., or thereabouts, is preferably employed at the outlet from the heating coil to which high-boiling fractions of the charging stock are supplied and preferably a superatmospheric pressure of from 100 to 500 pounds, or thereabouts, per square inch, is employed at this point in the system and may be either substantially equalized or reduced in the succeeding vaporizing and fractionating column. The heating coil of the last conversion stage of the process, to which only reflux condensate from the same stage is returned for further conversion, may utilize an outlet conversion temperature, for example, of from 850 to 950° F., or thereabouts, preferably with a superatmospheric pressure, measured at the outlet from the heating coil, of the order of 100 to 500 pounds, or more, per square inch. As already mentioned, substantially the same or somewhat reduced superatmospheric pressure may be utilized in the succeeding reaction chamber, when such a zone is employed, and a substantially reduced pressure ranging, for example, from 100 pounds, or thereabouts, per square inch to substantially atmospheric is preferred in the vaporizing chamber. Substantially equalized or somewhat reduced pressures, relative to that employed in the vaporizing chamber, may be utilized in the succeeding fractionating, condensing and collecting portions of the system.

As a specific example of one of the many possible operations of the process of the present invention as it may be practiced in an apparatus such as illustrated and above described: the charging stock is an Oklahoma crude of about 50° A. P. I. gravity, containing about 50 percent of material boiling up to 400° F. but of poor anti-knock value, and the charging stock is subjected to fractional distillation whereby about 27 percent of light gasoline fractions, having an end-boiling point of about 250° F. and of good antiknock value are recovered. Intermediate fractions of the charging stock, boiling between approximately 250 and 550° F. and comprising about 43 percent of the crude, are subjected to a conversion temperature of approximately 980° F. at a superatmospheric pressure of about 800 pounds per square inch. The remainder of the charging stock, comprising its high-boiling fractions, are separately subjected to a conversion temperature of about 920° F. at a superatmospheric pressure of about 300 pounds per square inch. A motor fuel of about 350° F. end-boiling point and of good antiknock value is recovered as the light distillate product of the last mentioned cracking stage. Intermediate fractions from this stage of the process, boiling between approximately 350 to 550° F. are returned to the heating coil of the first mentioned cracking stage, for further conversion together with said intermediate fractions of the charging stock. The higher boiling conversion products from the last mentioned cracking stage are commingled with the highly heated products from the heating coil of the first cracking stage and the commingled oils are introduced into a vaporizing chamber operated at a superatmospheric pressure of about 75 pounds per square inch. Vapors from the vaporizing chamber are subjected to fractionation whereby a motor fuel of about 400° F. end-boiling point and of good antiknock value is recovered as the overhead distillate product and reflux condensate from the fractionator is subjected to further conversion at a temperature of about 950° F. and a superatmospheric pressure of approximately 400 pounds per square inch and the resulting vaporous and liquid conversion products are introduced into the vaporizing chamber.

An operation such as above described may yield, per barrel of charging stock, about 70 percent of motor fuel having an antiknock value equivalent to an octane number of approximately 72 and about 20 percent of good quality fuel oil residue, the remaining 10 percent, or thereabouts, being chargeable, principally, to uncon- densable gas and loss.

I claim as my invention:

1. In a process for the conversion of hydrocarbon oils wherein raw oil charging stock for the process is subjected to fractional distillation to separate it into desirable low-boiling components, which are condensed, intermediate components and high-boiling components, the intermediate components subjected to pyrolytic conversion at elevated temperature and superatmospheric pressure, the high-boiling components subjected to pyrolytic conversion under relatively less severe conditions of elevated temperature and superatmospheric pressure and the products resulting from said pyrolytic conversion of the high-boiling components subjected to vaporization and fractionation whereby they are separated into desirable low-boiling products, which are condensed, insufficiently converted in

jecting a hydrocarbon distillate to cracking conditions of temperature and pressure in a heating coil and subsequently discharging the same into a reduced pressure vaporizing chamber, simultaneously subjecting a topped crude oil in a second heating coil to a relatively mild cracking treatment of a viscosity reducing character and subjecting the resultant products to vaporization and fractionation independently of the heated products from the first-named coil, supplying bottoms and reflux condensate from this vaporization and fractionation stage to said chamber and first-named coil respectively, separating vapors from unvaporized oil in said chamber and withdrawing the unvaporized oil from the process, fractionating the vapors to condense heavier fractions thereof and subjecting resultant reflux condensate to independently controlled cracking conditions of temperature and pressure in a third heating coil maintained at higher temperature than said second coil, introducing conversion products of the last named reflux condensate into said chamber, and finally condensing the fractionated vapors.

25 6. A conversion process which comprises subjecting a straight run hydrocarbon distillate to cracking conditions of temperature and pressure in a heating coil and subsequently discharging the same into a reduced pressure vaporizing

chamber, simultaneously subjecting a topped crude oil in a second heating coil to a relatively mild cracking treatment of a viscosity reducing character and subjecting the resultant products to vaporization and fractionation independently 5 of the heated products from the first-named coil, passing bottoms from this vaporization and fractionation stage to said chamber, supplying reflux condensate from said stage to the first-named coil for cracking treatment therein together with said straight run distillate, separating vapors from unvaporized oil in said chamber and withdrawing the unvaporized oil from the process, fractionating the vapors to condense heavier 15 fractions thereof and subjecting resultant reflux condensate to independently controlled cracking conditions of temperature and pressure in a third heating coil, introducing conversion products of the last-named reflux condensate into said chamber, and finally condensing the fractionated 20 vapors.

7. The process as defined in claim 6 further characterized in that said straight run distillate contains hydrocarbons boiling within the gasoline range and is subjected in the first-named 25 coil to higher cracking temperature than the last-named reflux condensate in the third coil.

KENNETH SWARTWOOD.
